THOMAS W. SPAULDING, OF BUFFALO, NEW YORK, ASSIGNOR OF ONE-HALF TO JOHN C. LEHNE, OF NEW YORK, N. Y.

GAME DEVICE.

Application filed August 24, 1927. Serial No. 215,121.

This invention relates to game devices and particularly to the type played with balls. An object of this invention is to provide an improved game device which will be interesting to both children and adults; which may be played with or without special grounds or courts; which will give opportunity for the exercise and development of considerable individual skill; with which any number of persons may play together; and which will be relatively simple, compact, and inexpensive.

A further object of the invention is to provide an improved game device which may be used in a variety of different ways for the purposes of physical and mental development; which will cause a player to partake of exercises involving muscles otherwise not sufficiently exercised in ordinary activities; which may be used in playing simple games or in more strenuous and complicated games; and which may be packed or shipped in a relatively flat, compact package ready for use.

Various other objects and advantages will be apparent from the following description of an embodiment of the invention, and the novel features will be particularly pointed out hereinafter in connection with the appended claims.

In the accompanying drawings:

Fig. 1 is a plan of a racquet constructed in accordance with this invention;

Fig. 2 is a side elevation of the same;

Fig. 3 is a fragmentary, sectional elevation of a part of the net device, with the section taken approximately along the line 3—3 of Fig. 1;

Fig. 4 is a plan, partly in section, of a portion of the racquet, and illustrating the manner of connecting the net device to the paddle.

Fig. 5 is a plan of a racquet also constructed in accordance with the invention, but illustrating another embodiment thereof;

Fig. 6 is a side elevation of the same; and

Fig. 7 is a plan partly in section of a portion of the same.

In the embodiment of the invention illustrated in Figs. 1 to 4, the improved racquet comprises a paddle or bat 10 having at one end a handle 11 by which it may be grasped in a player's hand and manipulated. A net device 12 is secured to the opposite end of the paddle, so as to form a continuation or

extension thereof in an endwise direction. While the net device may be secured to the end of the paddle in various ways, I preferably make the end edge 13 of the paddle which is opposite from the handle concavely 60 arcuate, and provide a groove 14 (Fig. 4) along this concave end edge. The side edges of the paddle may also be grooved lengthwise for some distance from their junction with the concave edge wall 13, so as to provide a groove 15 in each side edge of the paddle and extending to the concave end edge 13.

A wire frame or loop 16, having a center of curvature approximately co-incident with 70 the center of curvature of the concave edge 13, is disposed in the groove 14 in the end edge 13 so as to extend endwise from the paddle in a plane approximately parallel to a face of the paddle. Arms 17 are secured 75 to the loop in any suitable manner, such as by soldering, brazing or welding, and these arms extend along the side edges of the paddle from the concave edge 13, the arms fitting in the grooves 15 in the side edges and 80 conforming closely to the curvature of the side edges of the paddle. The ends of the arms 17 may be bent angularly to form hooks 18 which hook into recesses or cavities in the side edges of the paddle, so as to prevent 85 endwise movement of the arms along the grooves 15. The arms 17 may be confined within the grooves 15 in any suitable manner, such as by two-pronged staples 19, the prongs of which straddle the arms and are 90 driven into the paddle.

The net element may comprise an ordinary net, but preferably is provided in its center with a disk or pad 20 smaller than the opening of said frame or loop. This pad 20 may 95 be connected to the wire loop 16 in any desired manner which will not offer too great an obstruction or resistance to the passage of air therethrough, such as by well-known netting. Preferably, however, the pad 20 is 100 connected to the wire loop 16 by a plurality of strips 21 of suitable flexible sheet material, such as fabric. These strips 21 are secured in any suitable manner, such as by stitching, to the pad or disk 20, so as to radiate therefrom, and the free ends of the strips are looped or folded over spaced portions of the wire frame or loop 16, and the ends then stitched to the bodies of the strips, so as to be retained on the wire loop 16. I have 105 110

found that canvas or other heavy textile materials are satisfactory for the strips 21, and the pad 20 may be formed of one or more layers of canvas or other fabric, or of leather, thin wood, or other suitable material. The net element, however, is secured to the wire loop 16 before the latter is attached to the paddle and therefore some of the looped ends of the strips 21 covering the portion of the loop received in the concave end edge 13 will be received in the groove 14 of that edge.

In the embodiment of the invention illustrated in Figs. 5 to 7, the bat or paddle 10^a is similar to the bat or paddle 10 of Figs. 1 to 4, with the exception that the grooves 15^a at the side edges of the paddle decrease in depth from the concave end edge and gradually become flush with the side edges of the paddle. The wire frame or loop 16^a, similar to the frame 16 of Figs. 1 and 4, is provided with arms 17^a, similar to the arms 17 of Figs. 1 and 4, disposed in the grooves 15^a. The arms 17^a extend up to and beyond the ends of the grooves 15^a and terminate in loops or eyes 22 which lie flat against the side edges of the paddle. Suitable fastening elements such as screws 23 are passed through the loops or eyes 22 and into the paddle so as to secure the arms 17^a securely to the paddle.

The wire frame or loop 16^a, however, at the portion within the groove 14 at the concave edge of the paddle, is bent or formed to provide a prong or spike 24 which is driven into the concave end edge of the paddle through the bottom of the groove 14, in order to more effectively anchor the wire frame or loop to the paddle. This prong or spike 24 is, however, driven into the paddle before the arms 17^a are secured to the paddle. The net element 21^a may be formed as in Figs. 1 to 4, or of a single piece of fabric cut from a suitable pattern and stitched together as at 25 so as to be bowl-shaped.

The net element along its larger end or opening is looped over the wire loop or frame 16^a so as to be supported therefrom, and the opening 26 at the smaller end of the bowl-shaped net element may be closed by a disk-like base 20, as in Figs. 1 to 4, or by a base 20^a formed of a series of strips extending from different points of the smaller end of the bowl across the opening 26.

These strips of base 20^a may be interlaced together in any suitable manner so as to prevent the passage of a ball through the opening 26, at the same time providing air spaces through which air trapped in the net element may pass in order that the net element will not encounter too great an air resistance when the racquet is manipulated in use. The net element and the strips of base 20^a thereof may be formed of canvas,

fabric, leather, or any other suitable material.

In the use of this improved game device, each player is provided with a racquet constructed in accordance with this invention, 70 and the player grasps the racquet by the handle 11. A suitable ball, preferably a soft rubber ball or the like, is utilized and a player using the paddle as a bat, bats the ball in a manner well understood towards another player, and the other player toward whom the ball is batted, is expected to catch the ball in the net at the end of the paddle in a manner to cause the ball to enter the net device thereof. If the player to whom the ball is batted does not catch the ball in this manner, it counts against him, according to predetermined values, and if the ball is caught, it is removed for use by the player catching the same. This player now 80 in possession of the ball bats it either to the first player or to another player, in the same manner as described for the first player, and this is continued.

If one player alone is playing, the ball 90 may be batted against a wall, so as to cause it to rebound and the player batting the ball is then expected to catch it on the rebound by means of the net device on the end of his paddle. A single player may also bat the ball upwardly and then catch the descending ball in the net device of his paddle while manipulating the paddle by means of the handle thereof. Where several players are playing together, a suitable court 100 may be laid out and the ball played back and forth between opposed players according to a variety of rules, the ball being caught in the net device by each player. Various other uses and rules for the use of the game device will suggest themselves.

During the use of this improved racquet, if the net device is made relatively shallow, the disk or base 20 or 20^a will pass through the opening of the wire loop when the racquet is swung, and the ball missed, and will take up the same position on the opposite side of the loop or wire frame forming part of the net device. It will be observed that the racquet may be used to catch balls coming in either direction with respect to the faces of the paddle, irrespective of which face of the paddle the net element happens to be at the side of when the ball is received in the net device.

If the net element is made deeper, then the base 20 or 20^a by inertia, tends to move outwardly when the racquet is swung in catching a ball, and by striking against the wire loop 16 or 16^a or passing radially outwardly beyond the loop will prevent passage of the net element through the opening of the wire loop or frame and will thus always stay on the same side of the paddle regardless of how the paddle is manipulated in 120

playing. The base or disk 20 also keeps the net element open, and thus facilitates the removal of the balls from the net device after being caught.

5. It will be obvious that various changes in the details, which have been herein described and illustrated in order to explain the nature of the invention, may be made by those skilled in the art within the scope 10 and principle of the invention as expressed in the appended claims.

I claim as my invention:—

1. A game device comprising a paddle having at one end a handle and a wider flat, 15 even batting surface at the other end and an open-faced ball catching cup device secured to the said other end of the paddle so as to form a continuation thereof and opening in a plane approximately parallel to the face 20 of the paddle.

2. A game device comprising a paddle having at one end a handle, and a batting face at the other end, the end edge of said other end of the paddle having a groove extending along the same, a wire loop secured in said groove, and a net element attached to said loop.

3. A game device comprising a paddle having at one end a handle, and a batting face at its other end, said paddle having a groove extending along its end edge opposite its handle, a wire loop secured in said end edge groove of the paddle to form an extension of the paddle, arms extending from 25 the loop along and secured to the side edges of the paddle, and a net element attached to said loop.

4. A game device comprising a paddle having at one end a handle by which it may 40 be grasped in one's hand and manipulated, said paddle being grooved along its end edge opposite its handle and also along its sides for some distance from the grooved end edge, a frame secured in said end edge 45 groove, arms extending from said frame and extending along and disposed in the side edge grooves, means for securing the arms in said grooves, and a net element mounted on said frame.

5. A game device comprising a paddle having at one end a handle by which it may 50 be grasped in one's hand and manipulated, said paddle being grooved along its end edge opposite its handle and also along its sides 55 for some distance from the grooved end edge, a frame secured in said end edge groove, arms extending from said frame and extending along and disposed in the side edge grooves, said arms having angular portions preventing their endwise movement along the grooves in which they are mounted, means for securing the arms in said 60 grooves, and a net element mounted on said frame.

6. A game device comprising a paddle

having at one end a handle by which it may be grasped in one's hand and manipulated, a net device disposed at the other end of the paddle and having arms extending along the side edges of the paddle, and means for securing said arms to said paddle. 70

7. A game device comprising a bat having a handle at one end, a loop frame having a prong projecting into the opposite end of the bat, and arms extending from the 75 frame and secured to said bat whereby said frame forms an extension of said bat, and a ball-receiving net element carried by said frame.

8. A game device comprising a bat having 80 a handle at one end, a loop frame abutting the other end of said bat, said bat having grooves extending in directions lengthwise from the end adjacent said frame and ending flush with the surface of the bat some 85 distance from said frame, arms connected to said frame, running in said grooves and terminating in loops beyond the grooves, and fastening elements passing through the loops for anchoring the arms to said bat. 90

9. A game device comprising a bat having a handle at one end, a loop frame having a prong driven into the other end edge of said bat, said bat having grooves extending in directions lengthwise from the end 95 adjacent said frame and ending flush with the surface of the bat some distance from said frame, arms connected to said frame running in said grooves and terminating in loops beyond the grooves, and fastening elements passing through the loops for anchoring the arms to said bat. 100

10. A game device comprising a flat paddle having a handle at one end and its other end edge concave, said end edge being 105 grooved lengthwise, a loop frame fitted in said groove and having a prong extending from the portion within the groove and driven into the paddle through the concave end edge, and a net element carried by said 110 frame.

11. A game device comprising a flat paddle having a handle at one end and its other end edge concave, said end edge being 115 grooved lengthwise, a loop frame fitted in said groove and having a prong extending from the portion within the groove and driven into the paddle through the concave end edge, said frame having anchorage means extending therefrom along and secured to said paddle, and a net element carried by said frame. 120

12. A game device comprising a flat paddle having a handle at one end and its other end edge concave, said end edge being 125 grooved lengthwise, a loop frame fitted in said groove and having a prong extending from the portion within the groove and driven into the paddle through the concave end edge, said frame having arms extend- 130

- ing therefrom along the side edges of said paddle, means securing the ends of said arms to the paddle, and a net element carried by said frame.
13. A game device comprising a flat paddle having a handle at one end and its other end edge concave, said end edge being grooved lengthwise, a loop frame fitted in said groove and having a prong extending from the portion within the groove and driven into the paddle through the concave end edge, said frame having arms extending therefrom along the side edges of said paddle, the side edges of the paddle being grooved lengthwise for some distance from the concave end edge to receive and confine said arms, means securing the ends of said arms to the paddle.
14. A game device comprising a paddle having a handle at one end and a batting face at the other end, a wire strip bent into a loop with its adjacent ends bent laterally and outwardly of the loop and driven as a prong into the end edge of said other end, arms secured to spaced points of said loop and extending along and secured to said other end, and means carried by said loop forming an open-faced ball receiving cup.
15. A game device comprising a paddle having a handle at one end and a wider batting face at the other end, a closed ring disposed at said other end to form a continuation of said paddle, arms extending from spaced points of said ring, along and secured to said other end of the paddle to
- anchor said ring to said paddle, and means carried by said ring and forming an open-faced ball receiving cup.
16. A game device comprising a ball bat having a handle at one end and a batting surface at the other end, and an open-faced ball receiving flexible basket secured to and forming an extension of the said other end and having a depth less than approximately its diameter so as to pass through its open face and project to either side thereof when the bat is swung and then stopped suddenly, or when a ball strikes said basket while approaching its projecting face, whereby a ball may be caught in said basket from either face thereof.
17. A game device comprising a ball bat having a handle at one end and flat batting surfaces on both opposite faces of the other end, an open frame attached to and forming an extension of said other end with the opening of the frame approximately parallel to the batting surfaces, a flexible net element attached to said frame and forming therewith a ball-receiving basket, said net element having a depth less than approximately its diameter and being reversible to automatically pass through said frame and extend from either face thereof when the bat is swung and then stopped suddenly or a ball strikes said element while approaching its projecting face, whereby either face of said bat and basket may be used for batting or catching a ball.

THOMAS W. SPAULDING.
